Primary Examiner — Janice Hallmark(74) *Attorney, Agent, or Firm* — The Dobrusin Law Firm, P.C.(57) **CLAIM**

The ornamental design for a food cooling device, as shown and described.

DESCRIPTION

FIG. 1 is a right side elevational view thereof.

FIG. 2 is a left side elevational view thereof.

FIG. 3 is a front elevational view thereof.

FIG. 4 is a rear elevational view thereof.

FIG. 5 is a top perspective view of the present invention; and,

FIG. 6 is a bottom plan view thereof.

The broken lines showing environment in the drawings are for illustrative purposes only and form no part of the claimed design.
